CLAIM

The ornamental design for a cosmetic case, as shown and described.

DESCRIPTION

FIG. 1 is a perspective view of a cosmetic case showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof while in use. The broken lines shown in the FIG. 8 illustrate portions of the article and form no part of the claimed design.
